(57) **CLAIM**

The ornamental design for an architectural metal building panel, as shown and described.

DESCRIPTION

FIG. 1 is an upper left front perspective view of an architectural metal building panel showing my new design in accordance with a first embodiment of the present invention; FIG. 2 is a left side view thereof;

FIG. 3 is a front view thereof;

FIG. 4 is an upper left front perspective view of an architectural metal building panel showing my new design in accordance with a second embodiment of the present invention; FIG. 5 is a left side view thereof;

FIG. 6 is a front view thereof;

FIG. 7 is an upper left front perspective view of an architectural metal building panel showing my new design in accordance with a third embodiment of the present invention; FIG. 8 is a left side view thereof;

FIG. 9 is a front view thereof;

FIG. 10 is an upper left front perspective view of an architectural metal building panel showing my new design in accordance with a fourth embodiment of the present invention; FIG. 11 is a left side view thereof;

FIG. 12 is a front view thereof;

FIG. 13 is an upper left front perspective view of an architectural metal building panel showing my new design in accordance with a fifth embodiment of the present invention; FIG. 14 is a left side view thereof; and,

FIG. 15 is a front view thereof.

The broken line showings of FIGS. 1-15 are environmental only and not part of the claimed design. The right side views of the individual embodiments are not provided, as the right side view of each embodiment is a mirror image of the corresponding left side view. The claimed design is broken on one side to indicate indefinite length.
